Primary Examiner — Karen E Eldridge Powers*(74) Attorney, Agent, or Firm* — Taylor English Duma LLP(57) CLAIM

I claim the ornamental design for a floppy hat with netting under brim and bow, as shown and described.

DESCRIPTION

FIG. 1 is a perspective view of the claimed design.

FIG. 2 is a left-side elevation view thereof.

FIG. 3 is a right-side elevation view thereof.

FIG. 4 is a front elevation view thereof.

FIG. 5 is a back elevation view thereof.

FIG. 6 is a top plan view thereof; and,

FIG. 7 is a bottom plan view thereof.

The broken lines in the drawings are stitching and form a part of the claimed design.
